UNITED STATES PATENT OFFICE.

JOHN CHANDLER, OF BROOKLYN, NEW YORK.

RAILWAY DRAW-BRIDGE APPLIANCE.

SPECIFICATION forming part of Letters Patent No. 254,863, dated March 14, 1882.

Application filed December 6, 1879. Renewed February 10, 1882. (No model.)

To all whom it may concern:

Be it known that I, JOHN CHANDLER, of Brooklyn, in the county of Kings and State of New York, have invented certain Improvements in Railway Draw-Bridges and Safety Appliances relating thereto, of which the following is a specification.

The object of my invention is to provide against the possibility of a railway-train running into an open draw, and also to provide a means for controlling and stopping a runaway locomotive.

In the drawings, Figure 1 is a plan view of a railway draw-bridge and system of switches arranged according to my invention. Fig. 2 is an elevation of the same, looking in the direction of the arrow 2 in Fig. 1. Fig. 3 is an elevation of a portion of the safety-siding, looking in the direction of the arrow 3 in Fig. 1. Fig. 4 is a plan, on a larger scale, of the main track, and a portion of the sidings and draw, illustrating the switch-locking mechanism. Fig. 5 is a side elevation of the mechanism for operating the switch from the main track to the safety-siding. Fig. 6 is a plan of a device by which the said switch may be operated from the engine. Fig. 7 is a plan of a device by which the said switch will be operated automatically from the draw; and Fig. 8 illustrates my improved device for checking the backward motion of a runaway engine.

Let A represent the main or through track of the railway, B the draw-bridge, and C a safety-siding branching off from the track A at a switch, D.

E is a siding, which joins the siding C by a switch, F, and is preferably connected to the main track by a switch, G.

H is another siding, designed for use only in case of a runaway locomotive, and joined to the siding C by a switch, I.

The switch G has no immediate relation to my invention, and may be of any desired construction; but the switches D and F should be what are known as "safety-switches" or "tongue-switches," as shown in Fig. 4, and I prefer that the switch I should be of the same character. The switches D and F are each provided with a weight or spring, whose constant tendency is to cause the switches to stand as shown in Figs. 1 and 4, so that a train on the

track A running toward the draw will run off onto the siding C, and when it attempts to run back it will run onto the siding E instead of onto the main track.

In Fig. 5 is shown the mechanism for operating the switch D, consisting of the usual connecting-bar, a, and lever b, and with a weight, c, projecting laterally from the lever, as shown.

It will be observed that no means is provided for locking the switch, it being necessary for the switchman to hold the lever back in the position shown in dotted lines while the train is passing, and when he releases it it will immediately fall again to the position shown in full lines.

So far as described the operation is as follows: A train on the track A is approaching the draw, moving from right to left in Fig. 1. If the draw is closed, the line clear, and the switchman at his post, the latter will open the switch D to the through-track, and will stand and hold it open until the train passes. The train will then pass over the draw and continue on its course without interruption. If, on the contrary, the draw is open or the switchman is aware of any obstruction on the line, he will leave the switch D untouched; or, if the switchman is not at his post, the switch will remain untouched. Then when the train reaches the switch it will be directed onto the safety-siding C, where it will be gradually stopped in the manner to be hereinafter set forth. The engineer will then back his train, and it will be directed by the automatic switch F onto the siding E, where it may rest until the draw is closed or the obstruction ahead is removed.

The object of running the train back onto the siding E instead of onto the main track is twofold: first, with a single-track road, in case the obstruction on the line should be a train approaching in the opposite direction, that train will have clear passage, and a collision will be averted without delaying the moving train; second, in case another train is closely following the first, that train may run upon the siding C, and there remain until the first train is removed from the siding E. To bring the train from the siding to the main track again, that it may resume its course, the switch G will be set to the main track and the train backed.

onto that track; or other switches may be provided, if desired, whereby the train may be transferred from the siding to the main track. The draw being closed and the switch D properly set, the train may proceed upon its way.

From this description it will be seen that the only possibility of the train running into an open draw is in case the switchman were not aware of the draw being open and should open the switch D to the main track, and this contingency I provide against by the mechanism shown in Fig. 4, by which, whenever the draw is open, even enough to cause a non-coincidence of the rails, it will be impossible to open the switch D to the main track, and when the draw is closed and the rails coincide the opening of the switch D to the main track will lock the draw, so that that cannot be opened until the switch is closed again. A bolt, d, is arranged on the abutment of the draw-bridge, and capable of entering a socket on the draw when the latter is closed and the rails coincide. A rod, e, is fixed to the bolt and extends back to the operating mechanism of the switch D, with which it connects by a bell-crank, f, which works between two lugs on the rod a, or is connected in any other operative way. It will be seen that when the switch D is shifted to the main track the rod e is moved endwise to the left, thus projecting the bolt d into the socket and locking the draw.

I also provide a supplementary bolt operated by the draw-bridge, which locks the bolt d whenever the draw is opened and prevents its projection, except when the draw is fully closed. This supplementary bolt is lettered g in Fig. 4, and is operated by a tappet-lug, h, on the draw, acting upon a lever, i, to which the bolt g is pivoted, or of which it forms a part. A spring, j, is also provided to keep the bolt g pressed normally into a recess in the bolt d. When the draw is fully closed the bolt g is retracted and the bolt d and switch D are free to work; but when the draw opens the bolt g is protruded by the spring and locks the bolt d, so that that cannot be projected and the switch D cannot be shifted.

When it is desired to operate the switch D from the approaching locomotive, I employ the mechanism shown in Fig. 6, in which k is a lever which will be moved in the direction of the arrow by the flange of the wheel or by contact with some other part of the locomotive, and l is a lever which conveys the motion to a slider, m, moving that in the direction of the arrow. The slider is provided with a tooth which engages a notch, n, in the connecting-bar a of the switch and shifts the same. The draw-locking mechanism is substantially the same as shown in Fig. 4, except that the bolt d is provided with a handle by which to operate it at the draw, and the rod e is connected with the slider m by a link, so that its longitudinal motion causes a lateral motion of the slider sufficient to engage or disengage it from the notch n. It is shown as disengaged from the

notch, the bolt d being retracted. When the draw is in position and the bolt d projected to lock the draw the rod e draws the slider m toward the bar a and brings its tooth into engagement with the notch n, and the approach of a train will shift the switch to the main track. To hold the switch open when shifted and keep the weight e from shifting it back, a catch, o, may be provided, against which the end of the slider m will be caught when it has been moved in the direction of the arrow and is in engagement with the bar a. When the bolt d is retracted to open the draw the slider m will be pushed back until its end escapes from the catch o and its tooth from the notch n, when the weight e will shift the switch back to the position shown.

Fig. 7 shows a mechanism for shifting the switch automatically by the movement of the draw. h is a tappet-lug on the draw, and i a bell-crank, against one arm of which the tappet works, and the other arm is fixed to the end of a rod or wire rope, e, which leads to one arm of a bell-crank, f, the other arm of which connects with the switch-bar a. When the draw is closed the tappet h moves the lever i, which pulls the rope e, which moves the lever f, which shifts the switch. The rope or rod e should be incased in some non-conducting substance to protect it from heat and cold and prevent its too great expansion and contraction.

I prefer to construct the safety-siding C with a heavy upgrade from the switch D to its extremity, which grade shall act to check the speed of the train as it runs upon it and assist in stopping the same. The grade may be uniform, or, as I prefer, it may become steeper toward its extremity. A modification of my invention in this respect would consist in making the siding C level and in the form of a large circle, around which the train may run until it is stopped. As this circular track will require but little grading, it may sometimes be cheaper than to build an embankment to secure the necessary grade for the straight track.

In case of a runaway locomotive upon the line my invention will operate as follows: The switch D being in its normal position, the locomotive will be directed onto the side track, C, and its momentum will carry it to the extremity C' of this track, where the grade is so steep as not to be reached by an ordinary train, and it will pass the automatic switch I, and will stop either on the incline or at the buffer at the end of the track, when it will either stand still, where it can be boarded and controlled, or its weight will cause it to back down the incline and the switch I will direct it onto the track H, which, as shown in Fig. 2, has first a down and afterward an up grade, and on this track the locomotive will finally come to rest.

J J in Figs. 1 and 8 are pawls, which I provide, in connection with the graded tracks C and H, to stop the descent of an engine or car when desired. As shown in the side elevation, Fig. 8, this pawl is provided with a weighted

arm, *p*, which acts to keep the pawl-arm *q* lifted up sufficiently to engage the axle or some other part of an engine or car. A lever, *r*, is also provided, to depress the pawl-arm when it is

5 desired to release the engine or car and permit it to descend. A rubber cushion may be provided at the bearings of the pawl to reduce the force of the concussion should the engine or car have acquired any momentum when it
10 encounters the pawl.

I prefer to use a weight to control the switches D and F; but, if desired, a spring may sometimes be substituted.

If a siding is not desired in the vicinity of the 15 draw-bridge, the siding E, which I have herein described, and its switches F and G may be dispensed with without departing materially from my invention.

I have shown the railway on but one side of 20 the draw-bridge, as my arrangements may be exactly duplicated upon the other side of the bridge, if desired.

I claim—

1. The switch D, in combination with the 25 main track A, safety-siding C, and draw-bridge B, and provided with a weight, *c*, or its equivalent, tending constantly to open it from the track A to the siding C, substantially as and for the purposes set forth.

30 2. The combination of the main track A, draw-bridge B, and safety-siding C, having a heavy upward grade, and connected with the track A by a switch, D, which constantly tends to open it from the track A, substantially as
35 set forth.

3. The combination of the main track A, draw-bridge B, safety-siding C, and switch D with the connecting-rod *a* of that switch, the weight *c*, or its equivalent, tending to operate

it, the draw-bridge bolt *d*, and its rod or rope 40 *e*, whereby the opening of the switch D to the main track locks the draw-bridge in position, substantially as set forth.

4. The combination of the main track A, the draw-bridge B, the safety-siding C, and the 45 switch D with the connecting-rod *a* and weight *c*, or its equivalent, for operating the switch, and with the locking device at the draw, consisting of the bolts *d* and *g* and tappet *h*, and with the rod or rope *e* for connecting the locking device with the switch mechanism, whereby when the draw is open the switch is locked in position, substantially as set forth.

5. The combination, with the track A, draw 50 B, siding C, and switch D, of the siding E, connecting with the siding C by an automatic switch, F, operated by a weight, *c*, or its equivalent, whereby a train backing off from the siding C will be directed onto the siding E instead of onto the track A, substantially as set forth.

6. The combination of the track A, switch D, safety-siding C, having a heavy upward grade, switch I, and siding H, having a double grade rising in both directions toward its ends, substantially as and for the purposes set forth.

7. The sidings C and H, having upward grades toward the switch I, and provided with automatic pawls J J, consisting each of a pawl-arm, *q*, a weighted arm, *p*, and a depressing-lever, substantially as and for the purposes set forth.

In witness whereof I have hereunto signed my name in the presence of two subscribing witnesses.

JOHN CHANDLER.
